[57] **ABSTRACT**

An arrangement for inducing hypnosis includes a record medium subdivided into sections. A first section reproduces a message once for a predetermined period of time. A second section reproduces a second message repetitively for an indefinite period of time. A third section may be included to produce a message or alarm ending the period of hypnosis. Alternately, the alarm may be outside of the record medium.

METHODS AND MEANS FOR INDUCING HYPNOSIS

The inducement of hypnosis has become well recognized in recent years as being an effective method in aiding certain persons upset by physical and emotional problems. It has also been used to help people who merely desire to improve their mental abilities.

While the benefits to be derived from the use of hypnosis in many cases are numerous, unfortunately, many persons who can benefit therefrom are unable to do so. While some of these persons are unaware of the benefits they could achieve, in the main, the failure of many persons to take advantage of hypnosis is caused by the shortage of competent doctors in this field.

While the methods involved in hypnosis vary among different doctors, in many fields involving mental and emotional problems, the methods employed have generally involved a relatively fixed pattern. As the field of hypnosis has entered the phase where it is now considered somewhat of a science by many professionals and institutions, certain procedures and steps have been generally accepted as standard in the hypnosis field.

In many treatments involving hypnosis, there is a period known as the "induction" period. During this period, a doctor speaks to a patient for the purpose of producing a state of mind wherein he will accept the idea that he can be hypnotized. Once he accepts this idea, the patient becomes more susceptible to suggestions and treatments to follow. The induction period may last some predetermined period of time.

Following the induction period, the doctor may make a series of suggestions to the patient. This may be called the "suggestion" period. In most cases, these suggestions are repetitive in nature and designed to induce deeper and deeper responses within the patient.

The particular suggestions presented during the suggestion period are dependent upon the problem associated with the patient. For example, suggestions relating to physical ailments would be different than those for mental or emotional problems. In some cases, the hypnosis may be induced to overcome certain weaknesses of personality or may be made to assist the patient in relaxing in concentration to help him in speed reading, help the patient's memory or for any one of a number of other reasons.

Following the suggestion period, the patient is taken out of the hypnotic state. In most cases following the hypnosis, the problem being treated is alleviated. For example, the patient's memory may be improved, his concentration improved or the like. In many cases, a number of treatments may be necessary before an appreciable improvement takes place.

It is an object of this invention to provide improved method and means for producing hypnosis by means of a recording medium.

It is a further object of this invention to provide an improved means for producing hypnosis wherein a recording medium may include a plurality of messages for reproduction for different periods of time.

It is still a further object of this invention to provide an improved means for producing hypnosis including a record wherein means are included in the record to end the period of hypnosis.

In accordance with the present invention, means for inducing hypnosis in a person includes a recording medium. The recording medium is divided into two or more sectors each including a different recorded message. Means are provided to reproduce a first message on the first sector once or for some predetermined period of time. This first message relates to the induction period of the hypnosis operation. The second message recorded on the second sector is reproduced and played over and over in a repetitive fashion. Means for ending the period of hypnosis, which may include an alarm, may be separate from the recording medium or included in the recording medium to reproduce an alarm after the second message has been played for a predetermined period of time.

Other objects and advantages of the present invention will be apparent and suggest themselves to those skilled in the art,

from a reading of the following specification and claims, in conjunction with the accompanying drawing, in which:

FIGS. 1, 2 and 3 represent different embodiments of records which may be employed in practising the present invention, and

FIGS. 4, 5 and 6 represent different arrangements for utilizing magnetic tape, in accordance with the present invention.

Referring particularly to FIG. 1, a phonograph record 10 which, for example, may comprise a conventional 12 inch size 10 commonly used to be rotated at a speed of 33½ revolutions per minute on a conventional phonograph mechanism, includes three portions 12, 14 and 16.

In the present invention, the portion 12 is used to record the induction portion of an hypnosis period. The portion 16 includes the suggestion portion of the hypnosis period. The portion 14 includes no recording thereon and is used as a landing area for a tone arm of a record player, for a purpose to be hereinafter described.

The various phonograph mechanisms for reproducing the information on the record 10 are not shown or illustrated in detail because they may be conventional and are well known to those skilled in the art. For example, a feature found in phonographs sold commercially which is used in the present invention involves an arm adapted to rest on a top record 20 when a stack of records are being played. This arm serves to hold the records in place and upon playing of the last record serves to automatically shut off the phonograph.

If the arm referred to is not disposed over the last record to 30 be played but rather is disposed off to the side of the record, the various switching devices for turning off the phonograph will not become operative and the last record will be played over and over until the phonograph is manually turned off.

It is also well known in the art to have phonographs 35 designated to operate at different speeds, for example, 16 rpm, 33½, 45 rpm and 78 rpm. The present invention contemplates the use of a phonograph having such different speeds in some embodiments. The present invention further contemplates the use of stereophonic records involving dual tracks, 40 although for purposes of simplicity and explanation, only records with single information tracks are illustrated and described.

In one embodiment of the present invention illustrated in FIG. 1, the record 10 may be cut to reproduce intelligence 45 when it is played at a speed of 45 rpm. However, the actual size of the record may be much larger than that of a conventional 45 rpm record. As mentioned, the size of the record 10 may be the same as a conventional 33½ i.e. 12 inches. In effect, the record 10, which is the same size as a 33½ record, is 50 cut to be played at a speed of 45 rpm.

When the record 10 is placed on a phonograph of the conventional type adapted to reproduce records of different sizes and speeds, the arm for terminating the playing of the last record is positioned so that the record 10 will play over and over. The phonograph is also set to play at a speed of 45 rpm.

The tone arm of the record player is then manually set close to the outer periphery of the record at the beginning of portion 12. The portion 12 of the record 10 is then reproduced in 60 the conventional manner through appropriate amplifiers and loudspeakers.

Upon completion of the reproduction of the portion 12, the tone arm of the phonograph continues through the relatively narrow portion 14 with no information thereon and then on to 65 the portion 16. The audio signals recorded on portion 16 are then reproduced in the usual manner.

Upon completion of the playing of the portion 16, the automatic changing mechanism found in conventional record players comes into operation. The tone arm is lifted from the record and normally would be returned to its starting point to play the entire record over. However, in the arrangement illustrated, the tone arm will not return to the beginning of the record. Because the mechanism is set to play a 45 rpm record, the tone returns to the normal starting point of a 45 rpm record of the conventional size.

This being the case, the stabilizing arm returns to the portion 14, which serves as a landing track. The portion 16 of the record 10 is then played over and over. Consequently, it is seen that the portion 12 of the record 10 is played once, with the portion 16 being played over and over indefinitely.

In a hypnosis operation, the portion 12 may include the induction portion with the portion 16 including the suggestions portion. The induction portion is played once with the suggestions portion played over and over. An external alarm may be provided to awake a person under hypnosis at the end of a predetermined time, at which time the phonograph would be turned off.

The use of a single record in place of a number of records to reproduce induction and suggestion portions has a number of advantages. The obvious one is that of economy.

An additional advantage over the use of two records resides in the fact that the second record, which normally would have to be played over and over, would not have the top guiding arm to keep it in proper alignment during the playing of the first record. This tends to produce instability with the likelihood that the second record will fall during the playing of the first one to possibly damage the record or tone arm of the record player. As mentioned, if the guiding arm were disposed over the top record with the two record arrangement the second record would shut off the phonograph and prevent the second record from being played over and over. Referring particularly to FIG. 2, a somewhat different embodiment of the present invention is illustrated. A phonograph record 18 includes a pair of tracks 20 and 22, with the tracks 20 being interposed between the tracks 22. The record 18 may be of any conventional size and again designed to be played on a conventional phonograph. To play the record, the tone arm of the phonograph is disposed off to the side of the record so that the record will be played over and over.

When the record 18 is in position on the phonograph, the tone arm is manually set on the track 20. The track 20 may include the induction portion and designed to be played a single time. Upon completion of the reproduction of the track 20, the tone arm is moved back towards the periphery of the record. However, instead of returning all the way to the track 20, the tone arm is returned to track 22 with the information recorded thereon being reproduced. The track 22 may include the suggestion portion of the hypnosis period and is designed to be played over and over. As mentioned, the track 22 is interposed between the grooves of the track 20. Sufficient spacing is provided at the start of the tracks 20 and 22 to permit a person to manually set the tone arm on the track 20 and not accidentally place it on the track 22 to start the operation.

The beginning of the track 22 corresponds to the starting point of a conventional record and may be rotated at any one of the conventional speeds found on conventional phonographs. Because of the spacing of the track 20 from the track 22, the size of the record employed may be slightly larger than the conventional record.

As in the case of the record illustrated in FIG. 1, an external alarm may be set to go off at the end of a predetermined time period to bring a person out of hypnosis, at which time the phonograph would be shut off.

In some cases, it may be desirable to have a record with a built in alarm as part of the record. This arrangement is illustrated in FIG. 3. A record 24 includes portions 26, 28 and 30 separated by portions 32 and 34.

The portions of the record 26 and 28 may be similar to the portions 12 and 16 of the record 10 illustrated and described in connection with FIG. 1. The portion 32 may correspond to the landing track portion 14 of FIG. 1. When the record 24 is placed on the phonograph, the portion 26 is played once with the portion 28 being played over and over. The tone arm normally returns to the landing track portion 32 in substantially the same manner as described in connection with FIG. 1 after the portion 28 has been played.

A counter 36 is provided to count the number of times that the tone arm 38 plays the portion 28. For example, a 75

microswitch or other suitable means may be actuated each time the tone arm 38 reaches the end track portion 34. At the end of a predetermined number of counts, the changing mechanism becomes disengaged by a landing control mechanism 40 causing the tone arm 38 to continue on to the portion 30, which includes an alarm signal to awaken a patient.

The counter mechanism may be set by a patient to some preselected number with each setting of the counter corresponding to a period of time. Consequently, when the embodiment of FIG. 3 is used, an external alarm is not necessary. While the use of phonograph records to carry out the subject invention has particular advantages with respect to economy, nevertheless, magnetic tapes involving specially designed equipment may also be used. Magnetic recording and reproduction are well known. Hence, details relating thereto in FIGS. 4, 5 and 6 will be omitted except as they pertain specifically to the subject invention.

Referring particularly to FIG. 4, a magnetic 50 tape includes three tracks 52, 54 and 56 having information recorded thereon. The track 52 may include induction voice information, the track 54 may include recorded suggestions and the track 56 may include a recorded alarm.

20 The tape 50 is passed through a transducer assembly 58 which includes magnetic read heads 60, 62 and 64 disposed to read the information on tracks 52, 54 and 56 respectively. The output signals from the read heads 60, 62 and 64 are applied to switches 66, 68 and 70, respectively, of a switching unit 72.

25 The switches 66, 68 and 70 are normally open with one of the switches adapted to be selectively closed by means of a timer 74. Output signals from one of the magnetic heads 60, 62, or 64 are applied through the switching unit 72 to an audio reproduction unit 76, which includes appropriate amplifiers 30 and loudspeaker.

35 In operation, an operator may set the timer so that switches 60, 62 and 64 are sequentially closed for predetermined periods of time. The switch 66 is first closed to cause the induction information on track 52 to be audibly reproduced by the reproduction unit 76. Following a relatively short time which may be in the order of fifteen minutes, for example, the timer 74 causes the switch 66 to open and the switch 68 to close. At this point, suggestions recorded on track 54 are reproduced by the reproduction unit 76. The timer 74 is set to keep the switch 62 closed for a relatively long period of time, which may be in the order of one-half hour, an hour or longer as determined by the operator or patient.

40 After a preset time, the switch 68 opens and switch 70 closes. At this point, an alarm signal recorded on the track 56 is applied to the reproduction unit 76 to awaken the patient. The alarm signal may, of course, take a variety of different forms including an audio signal of a fixed frequency.

45 Referring particularly to FIG. 5, an arrangement somewhat similar to the arrangement of FIG. 4 is illustrated. The same type of tape 50 may be employed with the same type tracks 52, 54 and 56 recorded thereon, as described in connection with FIG. 4.

50 In FIG. 5, the tape 50 is passed through a transducer box 78 including a single read head 80. A timer 82, which may be preset by an operator, is adapted to operate a relay 84, which may include a stepping switch. Operation of the relay 84 at predetermined times causes the head 80 to be sequentially moved from the track 52 to the track 54 and finally to the track 56. The output signals from the head 80 are applied to the audio reproduction unit 76 where the recorded signals are reproduced in the manner discussed in connection with FIG. 4.

55 Referring particularly to FIG. 6, the arrangement illustrated includes an endless magnetic tape 86 having an induction track 88 and a suggestion track 90 recorded thereon. The recorded signals are reproduced in the usual manner by an audio reproduction unit 92. A switching from the track 88 to the track 90 may be provided by means such as described in connection with FIGS. 4 and 5.

A separate timer-alarm unit 94 may be provided to produce an alarm after a predetermined period of time.

The endless tape arrangement of FIG. 6 affords the advantage that the suggestion portion of the hypnosis may be included in a relatively small amount of tape, since only repetitive recorded signals are involved.

The embodiment of FIG. 6 contemplates a small compact battery operated arrangement wherein the tape may be included in the form of cassette units sold commercially.

While some emphasis has been placed on the use of an alarm in an hypnosis session, it is recognized that parts of the suggestions would enable a person to wake up at any time, for example, upon hearing a telephone ring or some other external happening. Some doctors may include words to the effect that if the patient desires to awake before the alarm, he should simply say the word "awake." In most cases, however, the use of an alarm of some kind is desirable.

It is recognized that special tapes may be made for the specific purpose of carrying out the present invention, which generally involves playing a first portion once and a second portion indefinitely. For example, part of the tape may be differentiated physically by inclusion of metal to denote the separation of the two portions. The tape may be repetitively returned to this marking to permit playing of the second portion without returning to the first portion after it has been played once. The tape may include recorded signals to separate the two portions or any one of a number of other arrangements may be employed without departing from the scope of the present invention.

What is claimed is:

1. In combination with a phonograph player having automatic means for repeatedly returning a movable tone arm from a predetermined inward position to a single predetermined outward set down position after said tone arm has reached said inward position, a phonograph record comprising first and second spiral tracks having recorded thereon first and second messages, respectively, each of said first and second spiral tracks having a starting position and an end position, the starting position of said first track being provided on said record at a position spaced from the predetermined set

- down position of said tone arm said first track being disposed to receive said movable tone arm within said first track at said starting position thereof, said first track disposed to guide said tone arm as it proceeds within said first track from said starting position to said end position of said first track when said phonograph record is rotated, said second track being disposed to receive said tone arm at its starting position after said tone arm has reached the end position of said first track, said second track being disposed to guide said tone arm within said second track as it proceeds from said starting position to said end position of said second track, the end position of said second track is provided on said record corresponding to the position at which said automatic means becomes operative to return said tone arm from said predetermined inward position and said starting position of said second track is provided on said record at a position corresponding to the single predetermined outward set down position of said tone arm whereby said first track is preproduced once and said second track is repeatedly reproduced by said automatic record player.
2. The invention as set forth in claim 1 wherein said two tracks are separated by a land track area at said set down position of said tone arm.
3. The invention as set forth in claim 1 wherein said first and second tracks comprise a pair of interposed tracks having information recorded thereon.
4. The invention as set forth in claim 3 wherein said second track is disposed close to the periphery of said phonograph record to receive said tone arm at said predetermined set down position at the start of each repetitive reproduction of the information recorded on said second portion, with the said first track spaced inwardly towards the center of phonograph record to permit an operator to manually set said tone arm on said first track to permit information recorded thereon to be audibly reproduced once.
5. The invention as set forth in claim 1 wherein a third track is included near center of said record, with means being provided to cause an alarm signal recorded thereon to be audibly reproduced after the information on said second track has been reproduced for a predetermined period of time.
